UNITED STATES PATENT OFFICE

ERNEST NUTTING, OF MARSHALLTOWN, IOWA

RINSE TUB

Application filed December 17, 1928. Serial No. 326,564.

The present invention relates to improvements in rinse tubs and has for its principal object to provide a device that includes a pair of independent compartments mounted 5 on a wheel supported frame so that the device is rendered portable and movable from place to place, each of said compartments being filled from the bottom as well as being drained at the bottom.

10 A further object is to provide a rinse tub wherein a gutter extends around the lower portion of the tub for receiving the overflow at the top of each compartment whereby the scum and dirty water may at all times 15 be drained off by letting fresh water in at the bottom.

A further object is to provide a rinse tub of the above mentioned character that includes a particular pipe arrangement for supplying 20 water to the respective compartments, suitable gate valves being associated with the pipes to control the flow of water therethrough.

Another important object is to provide a 25 rinse tub that is simple in construction, inexpensive, strong and durable and further well adapted to the purposes for which it is designed.

Other objects and advantages will become 30 apparent during the course of the following description.

In the accompanying drawing, forming a part of this specification, and in which like numerals indicate like parts throughout the 35 same:

Figure 1 is a side elevation of the rinse tub embodying my invention,

Figure 2 is a bottom plan view thereof more clearly illustrating the pipe arrangement and the gate valves associated therewith,

Figure 3 is a top plan view of the rinse tub and

Figure 4 is a fragmentary vertical sectional view taken approximately on the line 4-4 of Figure 3.

In the drawings wherein for the purpose of illustration is shown the preferred embodiment of my invention, the numeral 1 50 designates generally my improved rinse tub,

the same comprising a substantially rectangular shaped frame 2 constructed of a series of sections constructed of band material, the adjacent ends of the sections being detachably connected together by means of 55 the connecting plates 3.

The corners of the rectangular frame are rounded and angle iron legs 4 depend from the corners of the frame 2 and casters 5 are mounted on the lower ends of these leg members to run freely on the floor or ground. The rinse tub is preferably of the same height as those washing machines now on the market and the provision of the casters on the lower ends of the leg members renders the device 60 portable so that the same may be moved from place to place.

A substantially rectangular shaped open top tub 6 is adapted to rest on the upper edge of the frame 2 and if desired the bottom of the tub may be concaved to facilitate the easy cleaning of the same. A central transverse partition 7 is arranged vertically in the tub to divide the same into independent compartments 8 and 9 respectively. 75 A rim 10 extends around the upper edge of each compartment to provide what I term as a splash guard.

Extending around the upper edge portion of the frame 2 is the gutter or trough 11 for 80 receiving the overflow from the compartment. A waste pipe 12 extends downwardly from the bottom of the gutter or trough 11.

An overflow conduit 13 is arranged at each end of the tub, the upper end portion of each 85 conduit being in communication with the respective compartment through the medium of the overflow opening 14 over which is arranged a screen 15.

The lower end of each overflow conduit is 90 open for disposition directly above the gutter 11 as clearly indicated in Figure 4. A filling and discharge opening 16 is arranged in the bottom of the compartment 8, a similar combined filling and discharge opening 17 being 95 formed in the bottom of the compartment 9 and a screen 18 is arranged over each opening as clearly indicated in Figure 3.

A pipe 19 extends transversely across the bottom of the compartment 8, one end of this 100

pipe extending through the forward side of the frame 2 and having connection with a rubber filling hose 20 that may be attached to a faucet for supplying fresh water to the pipe 19.

5 A valve 21 is associated with the forward end of the pipe 19 for controlling the supply of clean water to the pipe 19. A discharge pipe 22 extends downwardly from the opposite end of the pipe 19 for discharging the dirty water drained from the compartment and a control valve 23 is associated with the discharge end of the pipe 19 and the waste pipe 22.

15 A sectional pipe 24 that extends longitudinally beneath the tub 1 has communication at its intermediate portion with the pipe 19 through the medium of the cruciform formed shaped fitting 25.

20 One end of the sectional pipe 24 connects with the opening 16 formed on the bottom of the compartment 8, while the other end of the pipe 24 has connection with the opening 17 formed in the compartment 9.

25 Forming a salient part of the present invention are the gate valves denoted generally by the numerals 26 and 27 respectively and are arranged in the sectional pipe 24 on opposite sides of the fitting 25. These gate 30 valves control the flow of the water from the pipe 24 to the respective compartments and the actuating rod for these gate valves extend through the front side of the frame and have actuating handles 28 arranged on the outer 35 end thereof to facilitate manual operation of the gate valve.

A pipe and valve arrangement of this character enables either one or both compartments to be filled and drained and furthermore the overflow openings 14 will permit the dirty water and scum to be carried off into the gutter 11 and this is accomplished by letting fresh water in from the bottom.

40 It will thus be seen from the foregoing description, that I have provided a rinse tub that is capable of being readily and easily assembled or disassembled and furthermore the device will at all times be positive and efficient in carrying out the purposes for which 45 it is designed.

50 While I have shown the preferred embodiment of my invention, it is to be understood that various changes in the size, shape and arrangement of parts may be resorted to without departing from the spirit of the invention and scope of the appended claim.

Having thus described my invention, what I claim as new is:

55 A portable laundering unit for rinsing clothes comprising a supporting frame, a tub supported on the frame and presenting separate rinsing compartments, each of which has a drain opening, a pipe connecting said openings, and extending horizontally below the bottom of the tub, a second horizontal pipe

extending transversely of the said connecting pipe with its intermediate portion in communication with the latter and having its opposite ends terminating at the sides of the tub, a control valve associated with each pipe 70 end, a drain pipe extending downwardly from one of the said valves, a filling hose connected with the other valved end, and valves arranged in said connecting pipe on opposite sides of the communicating transverse pipe 75 and having their respective operating elements disposed for manual operation adjacent a common side of the said frame.

In testimony whereof I affix my signature. ERNEST NUTTING. 80
